INTERNAL COMBUSTION ENGINE

George A. Poll, Cincinnati, Ohio

Application July 13, 1942, Serial No. 450,731

7 Claims. (Cl. 123—53)

This invention relates to improvements in self-contained, self-propelled engines, such as the internal combustion type.

Internal combustion engines are well known, and particularly the engines such as used in the present day automobile of the four stroke type. In the engines as today employed, each cylinder and its piston is independent and operates or fires in an established order, whereby the power impulse or stroke is distributed along a crank shaft, so as to obtain as smooth and continuous a rotation of said crank shaft as possible. With most engines, ignition takes place at approximately the top dead center; in fact one half of the combustion and therefore one half of the pressure is developed at the time of dead center, and likewise with most engines the total combustion is completed at approximately 25° past dead center. It is at this precise moment that the pressures are the greatest, and the crank below the piston is not at any advantageous angle for converting these pressures into work.

With this invention the possibility of ignition on top dead center of the piston is eliminated, as provision is made whereby the piston unit to be fired is always beyond this top center position when the spark is supplied thereto.

It is therefore the principal object of this invention to provide a piston type engine wherein the crank is so disposed angularly as to turn these pressures into work as soon as they are developed.

Another object of this invention is the provision in an internal combustion engine of means which insures a cylinder of each unit of a multi-cylinder engine being off center in the direction of its drive at the time when the firing occurs and when the compression pressure is the greatest.

Another object of this invention is the provision of an internal combustion engine, wherein all of the residual gases, after a power stroke, are practically eliminated from the cylinder unit before being charged with raw gas for subsequent firing.

It is also an object of this invention to provide an internal combustion engine, which, in view of the foregoing objects, can be made somewhat lighter in construction due to its efficient operation and conversion of heat, to power in view of the fact that no resistance within the engine is encountered at the time that the explosion within the cylinder takes place.

Other objects and advantages of the present invention should be readily apparent by reference

to the following specification considered in conjunction with the accompanying drawings forming a part thereof and it is to be understood that any modifications may be made in the exact structural details there shown and described, within the scope of the appended claims, without departing from or exceeding the spirit of the invention.

In the drawings:

Fig. 1 is a top plan view of a portion of an internal combustion engine embodying the improvements of this invention.

Fig. 2 is a view partly in section and partly in elevation, as seen from line 2—2 on Fig. 1.

Fig. 3 is a transverse sectional view taken on line 3—3 on Fig. 2.

Fig. 4 is a view, on a smaller scale, of a portion of a crank shaft that may be employed for accomplishing the objects of this invention.

Fig. 5 is a fragmentary sectional view of a portion of an engine, showing a modification.

Fig. 6 is a transverse sectional view on line 6—6 on Fig. 5.

Fig. 7 is a fragmentary sectional view taken on line 1—1 on Fig. 5.

Fig. 8 is a fragmentary plan view of a portion of the engine as seen from line 8—8 on Fig. 7.

Fig. 9 is a perspective of the valve shown in the modification and forming a detail of the invention.

Throughout the several views of the drawings, similar reference characters are employed to denote the same or similar parts.

As was noted above, this invention pertains in general to an engine of the reciprocating piston type, and particularly to internal combustion engines, where it will probably find its greatest use. The accomplishment of the objects initially set forth will become evident as the invention is specifically described.

In general the invention comprises a housing, comprising a cylinder block 10, to which is secured, in the usual manner, the cylinder block head 11 at its upper end, and the oil pan or crank case 12 at its lower end. The cylinder block 10 is provided with a plurality of parallel cylinders or piston bores 13, 14 and 15 and 16, being all that are illustrated in the drawings, but it is understood this may be increased, and in fact would be doubled to provide what is generally known as a four cylinder engine. As illustrated in the drawings, cylinders 13 and 15 are illustrated as of a similar diameter and are smaller than the cylinders 14 and 16, with cylinders 13 and 14 forming one unit, while cylin-

ders 15 and 16 form a second unit, and these units are multiplied as desired; there being four such units in what has been heretofore known as a four cylinder motor, six units in a six cylinder motor, etc.

Each of the cylinders may be encircled by a water jacket 17 which would be communicable with one another through passages in the head 11, or the said cylinders may be air cooled, as desired and well known. Disposed in each cylinder unit, such as 13 and 14, are pistons 18 and 19 of a diameter corresponding to its cylinder, and each piston is further provided, as is usual practice, with piston rings 20. The wall 21 between cylinders 13 and 14 is relieved at its top, as at 22, to provide a passageway 23 between the cylinders 13 and 14 whereby the pressure in said cylinders may be equalized.

Extending through the cylinder block head 11 are supply ports 24 and 25, respectively supplying the cylinders 13 and 14 with the gas mixture to be subsequently exploded. Likewise extending through the cylinder block head 11 are exhaust ports 26 and 27, respectively connected with cylinders 13 and 14, for permitting the escape of residual gases in said cylinders after the explosion. Each of the ports 24 to 27 inclusive is provided with a similar valve 28, each having extending therefrom a valve stem 29. Each valve stem 29 passes through a guide 30 located above its port. Each valve stem 29 is provided on its upper end with a head 31, forming one abutment for a spring 32, which abuts on its other end with the valve stem guide 30. As is well known, the spring 32 maintains the valve against its seat to prevent passage through its port except when the cylinder is being charged or discharged.

It will be understood that each cylinder unit, such as 15 and 16, is provided with similar valves for each of its individual cylinders.

The ports 24 and 25, as well as the supply ports to each of the other cylinder units, are supplied through an intake manifold 33, which extends from the usual carburetor or other fuel supplying device. As illustrated in the drawings, the intake manifold 33 is shown as formed partly of the cylinder block head 11, but this intake manifold may be an independent supply system bolted or otherwise secured to the cylinder block, as is the usual practice.

The exhaust ports 26 and 27, as well as the exhaust ports of all of the other cylinder units of a given engine, are likewise connected with a manifold, usually termed an exhaust manifold 34, which extends to the atmosphere, usually through a muffler, as again is usual practice. It will be noted that the exhaust manifold is illustrated as formed integral with the cylinder head 11, which again may be a separate system bolted or otherwise secured to the cylinder block itself.

In order to explode the gaseous fuel within the cylinders, each cylinder is provided with the usual spark plug or other spark producing mechanism 35, each of which has extending from it an electric current conductor, such as a wire 36. The said wires 36 extending from the spark plugs terminate in a distributor 37, which through the usual timing mechanism distributes the electrical impulses among the cylinders in the order in which they are to be fired, as is usual practice. It will be noted, that the wires 36', from the spark plugs of the cylinder unit 13-14 have a common terminal in the distributor 37, as have the wires 36'' from the cylinder unit 15-16. Each subsequent pair of cylinder units likewise

has a pair of wires with a common terminal in the distributor. By this construction the compressed fuel gas in each cylinder unit is simultaneously exploded for driving the two pistons in each unit simultaneously in a power delivering stroke direction.

Each of the pistons 18 and 19 is provided with a connecting rod 38 and 39, each connected with a crank pin 40 and 41 of the crank shaft, indicated 10 as a unit by the reference character 42. The crank shaft 42 is mounted in bearings at opposite ends of the crank case 12, one of which bearings is indicated at 43 in Figs. 2 and 5. The crank shaft 42 exteriorly of the crank case 12 is provided with means, such as gear 44, for transmitting power to, for example, the drive shaft of an automobile.

As illustrated in Fig. 3, the crank pins 40 and 41 are of an equal distance from the center of the crank shaft 42, but one of the said crank shaft pins is angularly disposed ahead of the other. As illustrated in Fig. 3, the crank pin 41 is shown as directly vertical of the crank shaft 42 with its piston at the upper end of its stroke, while the crank pin 40 is illustrated as in advance of the crank pin 41 and with its piston 18 as withdrawn from the upper end of its stroke. This angle, as shown in the drawings, is 35 degrees, thereby placing the crank pin 40 in an advantageous position to receive the driving impulse, as would be effected upon explosion of the compressed gases within the cylinder. It should be noted that the crank shaft 42 is to be rotated in a clockwise direction as indicated by the arrow 45 on Fig. 3.

In operation and with reference to the drawings, it is assumed that the piston 19 has reached its full compression stroke and that the distributor 37 has sent an electrical impulse to the spark plug 35 for igniting the fuel. It will be appreciated that initially the piston 19 will respond slower than the piston 18, due to the fact that the piston 19 is in its dead center position, while the piston 18 is in an advanced position, and will therefore be able to take advantage of the full impact of the explosion.

While an advance of 35°, as illustrated in the drawings, of the piston cranks gives efficient results, this angularity may be reduced to 20° or 50 may be increased to 60° with material advantage over the engines as today employed.

As is usual practice, the various intake and exhaust valves are opened during the intake stroke and the discharge stroke of the several pistons and to accomplish this, there is provided a rocker arm 46 pivotally mounted at 47 and having one end 48 engaging the valve stem head 31 and with the other end 49 of the rocker arm engaging the tappet rod 50. The lower end of the tappet rod 50 rides on the cam shaft 51 which is driven through a sprocket and chain mechanism 52, from the crank shaft 42.

From the foregoing, it is believed now evident that the objects initially set forth are accomplished and that a piston of each cylinder unit is always in position to take advantage of the maximum pressure developed.

In the modification disclosed in Figs. 5 and 6, the crank pin 41' is illustrated as of a greater distance from the center of the crank shaft than is the crank pin 40'. With this construction a greater stroke is given to the retarded piston, with said stroke extending between the top of the piston 19' illustrating the uppermost point of the upper end thereof and the phantom line 53 illus-

trating the lowermost point of the bottom of said piston 19', while the piston 18' travels from the phantom line 54, representing the top of its stroke in Fig. 5 to the phantom line 55, which illustrates the bottom of the piston 18'.

It may be desirable at times to completely separate the cylinders from one another as for example when exhausting one of the cylinders, the retarded cylinder, while the advance cylinder is being charged. To accomplish this, use may be made of a valve, such as 56, which is located at the upper end of the wall which separates said cylinders to close off the space 23. As shown particularly in Figs. 7 and 9 the valve 56 is provided with circular journal portions 57 and 58 journaled in bearings provided by the cylinder block 10 and its head 11. Between the journals 57 and 58 the valve has a body portion 59 with its upper half removed to form passage 60, which when in the position illustrated in Figs. 5 and 7 offers no restriction to passage through the way 23. If the valve is turned either clockwise or counter-clockwise the said passage 23 is cut off.

Any suitable or desirable means may be employed for rotating the valve and as shown in the drawings this means includes a reduced portion 61 projecting from one end of the valve to which is secured a lever 62, see Fig. 8. The outer end of the lever 62 is pierced to receive one end 63 of a rod 64 which has its lower end contacting and riding on the cam shaft 51. A cam 65 on the cam shaft effects the upward movement of rod 64 and through the lever 62 a rotation of the valve 56 to close off passage 23. In order to maintain contact of the rod 62 with the cam shaft 51 and cam 65 use is made of a spring 66 having one end secured to the lever 62 and the other end anchored to the cylinder block.

It is contemplated that the relation between the cam 65 and valve 56 is such that the valve will operate to close the passage 23 when the advance piston is about 160° past top center on a power stroke and will open said passage when the other or retarded piston has completed its exhaust stroke, that is, after both pistons have completed their exhaust strokes and are commencing a charging or intake stroke.

What is claimed:

1. In an internal combustion engine, a pair of cylinders each of a different diameter and each containing a piston for reciprocation therein, said pistons and cylinders operating as a unit and adapted to be charged with gaseous fuel to be exploded, means for effecting the simultaneous explosion of said fuel in each cylinder, and a crank shaft below said pistons and cylinders having a pair of crank pins respectively connected with said pistons and one of said crank pins being angularly advanced with respect to the other.

2. In an internal combustion engine, a pair of cylinders each containing a piston for reciprocation therein, said pistons and cylinders operating as a unit and adapted to be charged with gaseous fuel to be exploded, means for effecting the simultaneous explosion of said fuel in each cylinder, and a crank shaft below said pistons and cylinders having a pair of crank pins respectively connected with said pistons and one of said crank pins being farther removed from the crank shaft than the first crank pin and one of said crank pins being angularly advanced with respect to the other.

3. In an internal combustion engine, a pair of cylinders connected with one another by a passage way at their upper ends, a crank shaft below said cylinders, a piston in each cylinder, said cylinders adapted to be charged with gaseous fluid to be exploded, means associated with each cylinder for effecting the simultaneous explosion of said fuel in the cylinders, a crank pin on said crank shaft connected with one of said pistons, a second crank pin on said crank shaft angularly advanced with respect to said first crank pin and connected with said second piston, and means for closing said passage way.

4. In an internal combustion engine, a pair of cylinders connected with one another by a passage way at their upper ends and each cylinder of a different diameter, a piston in each cylinder, said cylinders adapted to be charged with gaseous fluid to be exploded, means associated with each cylinder for effecting the simultaneous explosion of said fuel in the cylinders, a crank shaft below said pistons and cylinders, a crank pin on said crank shaft connected with one of said pistons, a second crank pin on said crank shaft angularly advanced with respect to said first crank pin, and means for closing said passage way.

5. In an internal combustion engine of the four stroke cycle type comprising a plurality of piston and cylinder units, each unit comprising a pair of cylinders connected at their upper ends by a passage way, a piston in each cylinder, said cylinders adapted to be charged with gaseous fluid to be exploded, means associated with each cylinder for effecting the simultaneous explosion of said fuel in the cylinders, a crank shaft below said units, a crank pin on said crank shaft for each piston and connected therewith with one of said crank pins for each unit advanced with respect to the other, a valve in the passage way between the unit cylinders, and means for actuating said valve to close the passage way for a part of the stroke cycle of the pistons of each unit.

6. A piston and cylinder unit for an internal combustion engine of the four stroke cycle type comprising a pair of cylinders connected at their upper ends by a passage way, a piston in each cylinder, said cylinders adapted to be charged with gaseous fluid to be exploded, means associated with each cylinder for effecting the simultaneous explosion of said fuel in the cylinders, a crank shaft below said pistons and cylinders, having a crank pin for each piston with one of said crank pins in advance of the other and with one of said crank pins of a greater stroke than the other to effect a greater travel of its piston, a valve in the passage way between the cylinder, and means for actuating said valve to close the passage way for a part of the stroke cycle of the pistons.

7. In an internal combustion engine, a pair of cylinders each of a different diameter and each containing a piston for reciprocation therein, said pistons and cylinders operating as a unit and adapted to be charged with gaseous fuel to be exploded, means for effecting the simultaneous explosion of said fuel in each cylinder, and a crank shaft below said pistons and cylinders having a pair of crank pins respectively connected with said pistons and one of said crank pins being farther removed from the crank shaft than the first crank pin and one of said crank pins being angularly advanced with respect to the other.

GEORGE A. POLL.
